UNITED STATES PATENT OFFICE.

ARCHIE LIBERTY, OF AMASA, MICHIGAN.

MECHANICAL STARTER FOR INTERNAL-COMBUSTION ENGINES.

1,248,352.

Specification of Letters Patent. Patented Nov. 27, 1917.

Application filed September 30, 1915. Serial No. 53,325.

To all whom it may concern:

Be it known that I, ARCHIE LIBERTY, a citizen of the United States, residing at Amasa, in the county of Iron and State of Michigan, have invented certain new and useful Improvements in Mechanical Starters for Internal-Combustion Engines, of which the following is a specification.

This invention relates to the class of internal combustion engines, and more specifically to mechanical starters for internal combustion engines.

The object of my invention is to provide a mechanical starter for internal combustion engines which will be entirely spring operated, thereby doing away with the expensive and uncertain electric or air operated starters. My device is extremely simple and durable in construction, and could be installed as a part of internal combustion engines at a very small cost. The arrangement of my starter is such that it may be increased or decreased in power depending upon the engine upon which it is used, merely by the addition or subtraction of the number of coil springs forming a part thereof, and it may be used to start the engine a great many times without necessitating the rewinding thereof.

Other objects of this invention not at this time more particularly enumerated, will be clearly understood from the detailed description and drawings forming a part of this specification.

Furthermore, this invention consists in the novel arrangement and combination of parts more particularly described in the following specification and embodied in the claim appended hereunto and forming a part of this application.

Referring now to the drawings, which are merely illustrative of my invention,

Figure 1 is a longitudinal sectional view of my improved starter.

Fig. 2 is a cross-sectional view taken on the line 2—2 of Fig. 1.

Fig. 3 is a cross-sectional view taken on the line 3—3 of Fig. 1.

Fig. 4 is a top plan detail of the winding lever.

Referring further to the drawings, wherein similar reference characters designate similar parts throughout the respective views, 1 designates a casing of suitable size and shape provided with bearings 2 fixedly mounted therein and preferably coextensive

in size with the cross-section of the casing. A main drive shaft 3 is loosely mounted within said bearings 2 and extends longitudinally of the casing 1. A plurality of 60 coil springs 4 are spaced apart upon said shaft, between said bearings 2, one end of each of said springs being mounted upon said shaft 3, while the other end is secured to a stationary rod 5 interposed between said 65 bearings near the top thereof.

A ratchet disk 6 is keyed to the shaft 3 near the forward end thereof, while a pivoted arm 7, having a winding pawl 8 pivoted thereto near the upper end thereof, is 70 loosely mounted upon the end of said shaft 3. A support 11 secured to the bearing 2 is mounted within the forward end of the casing 1. A winding lever 12, one end of which is connected to the pivoted arm 7, and the 75 other end connected to a hand lever 13 by means of a connecting rod 14, is pivotally mounted upon said support 11. A reciprocating movement is thus applied to the arm 7 by means of levers 12 and 13, thereby 80 causing the ratchet disk 6 to be turned for winding the springs 4. A locking pawl 9 is pivoted to a support 10 secured to the end wall of the casing 1, said pawl being adapted to lock said ratchet disk 6 against reverse 85 movement upon each return of the arm 7.

A spring operated ratchet disk clutch 15 is mounted upon the opposite end of the shaft 3, said clutch consisting of a clutch disk 16 formed with sprocket teeth circumferentially thereof, and a sliding disk 25. 90 A sprocket drive chain (not shown) may be interposed between the clutch disk 16 and the crank shaft of the engine.

The releasing mechanism consists of a rod 95 17, slidably mounted within the bearings 2 and extending longitudinally of the casing 1, and is connected to a pedal lever 18 located at a point convenient to the operator. A shaft 19 is mounted transversely within 100 said casing near the forward end thereof. Upon said shaft is mounted a bell crank lever 20, one arm of which engages the rod 17 while the other arm is adapted to engage with the winding pawl 8. Stops 21 are 105 mounted upon the rod 17 on both sides of the arm of the bell crank lever 20. A lifting arm 22 is fixedly mounted upon the shaft 19 and is adapted to engage with the pawl 9. A clutch lever 23 is pivoted to a 110 support 24 mounted on the bearing 2 near the rear end of the casing 1. One end of the

lever 23 is pivoted to the rod 17, while the other end thereof actuates the sliding disk 25 of the ratchet clutch 15, springs 25^a being interposed between the clutch disk and the ratchet disk and between the clutch disk and the lever 23, respectively, whereby the various parts will be returned to inoperative position when pressure on the pedal lever 18 is removed.

- 10 Thus it will be noted that when it is desired to operate my device, the foot pedal is actuated, thereby causing the stops 21 to engage the bell crank lever 20, whereby said lever and said arm 22 will remove the pawls 15 8 and 9 respectively, from the ratchet disk 6. The movement of the rod 17 also actuates the clutch lever 23 which causes the sliding disk 25 to lock with the clutch disk 16. As the clutch is locked an instant prior 20 to the release of the ratchet disk 6, the unwinding of the springs 4 will cause the shaft 3 to rotate, thereby rotating the crank shaft through the medium of the sprocket chain whereby the engine is started.
- 25 When completely wound, the springs will actuate the starting mechanism of the engine a number of times before necessitating the rewinding thereof. To rewind said springs the winding pawl 8 is actuated by 30 means of the hand lever 13, whereby the ratchet disk 6 and the shaft 3 are rotated. As one end of each of the springs is fixed to said shaft, the rotation thereof will wind 35 said springs.
- 35 The utility, adaptability, and advantages of my improved form of mechanical starters for internal combustion engines being obvious, it is unnecessary to further enlarge upon the same herein.
- 40 Having now described and pointed out the new and useful features of my invention, I do not limit myself to the shape of

certain parts where the shape is not essential, nor do I restrict myself to the exact details of construction shown and described, 45 but mean and intend to claim all equivalents and variations thereof not departing in principle from my invention, and falling within the purview of the appended claim.

What I claim as my invention and desire 50 to secure by Letters Patent is:

A mechanical starter for internal combustion engines consisting of a casing, bearings mounted within said casing, a shaft rotatably mounted in said bearings, a rod interposed between said bearings, springs secured at one end to said shaft and at the other end to said rod, a ratchet disk keyed upon one end of said shaft, an arm pivotally mounted upon said shaft adjacent said ratchet disk, 60 a pawl mounted upon said arm adapted to actuate said ratchet disk, lever operated means connected to said arm adapted to actuate the same, a supporting member mounted upon said casing adjacent said 65 ratchet disk, a pawl mounted upon said supporting member adapted to prevent reverse motion of said ratchet disk, a shaft mounted transversely of said casing, a bell crank lever fixed to said shaft and adapted to disengage said last-mentioned pawl, an arm fixedly mounted upon said shaft adapted to disengage said first-mentioned pawl, a clutch mounted upon the other end of said first-mentioned shaft, an arm mounted 70 within said casing adapted to throw said clutch into operative engagement, and a lever operated rod slidably mounted within said bearings and connected to said last-mentioned lever and said bell crank lever 75 adapted to actuate the same.

In testimony whereof I affix my signature hereto.

ARCHIE LIBERTY.
